Primary Examiner — Derrick Holland*Assistant Examiner* — Jennifer O King*(74) Attorney, Agent, or Firm* — Patterson Intellectual Property Law, P.C.(57) **CLAIM**

What is claimed is the ornamental design for a modular inverter assembly case, as shown and described.

DESCRIPTION

FIG. 1 is an isometric view of a modular inverter assembly case according to the invention;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown represent portions of the modular inverter assembly case that form no part of the claimed design.
